(57) **CLAIM**

The ornamental design for a protection board mounting bracket, as shown and described.

DESCRIPTION

FIG. 1 is a rear perspective view of a portion of a protection board mounting bracket showing my new design;
FIG. 2 is a rear elevational view thereof;
FIG. 3 is a front elevational view thereof; and,
FIG. 4 is a bottom plan view thereof.
In the drawings, the broken lines depict unclaimed subject matter only and form no part of the claimed design.
